MELVILLE F. CLEMENTS AND NICK F. HELMERS, OF ST. PAUL, MINNESOTA

METHOD OF CONSTRUCTING SUBAQUEOUS FOUNDATIONS

Application filed April 25, 1929. Serial No. 357,995.

Our invention relates to improvements in the construction of foundations, and is particularly adapted for use in the construction of subaqueous foundations where the depth of water and/or the movement of the water, due to tides, waves or current, interfere with the use of methods heretofore practiced.

It is the object of our invention to provide a method of initiating the work of constructing a caisson of any desired type directly above the foundation to be constructed.

Further objects of our invention are: (1) to provide a method of constructing a caisson above the surface of the water; (2) to provide a method of constructing a caisson where the depth of the water and underlying soft material forming the bed of the water is too great to permit the economical construction of an exposed island of earth on which a caisson may be constructed; (3) to provide a structure for enclosing loose earth, such as sand or other granular material to form an island on which a caisson may be constructed above the surface of the water; (4) to provide means of lowering a caisson which has been constructed at or near the surface of the water down to stable material.

Referring to the drawings, Figure 1 is a plan view diagrammatically showing mechanism adapted to carry out our invention; Fig. 2 is a sectional view on the line 2-2 of Fig. 1; and Fig. 3 is a detail showing the sectional construction of the caisson cylinder.

In the drawings (see Fig. 2) the reference letter *a* indicates the surface of the water, *b* the soft or loose material forming the underwater surface of the ground, and *c* bed rock or other material upon which the foundation is to be placed.

In carrying out our invention, we first construct a shell or cofferdam, preferably in the form of a steel cylinder 1, of substantially greater diameter than the greatest horizontal dimension of the pier to be constructed, and sink said shell into the loose or soft material *b* in the bed of the water until its lower edge 2 reaches a stable support. To facilitate the placing and removing of the shell, we prefer to construct it of sectional rings 3 provided with internal annular flanges 4 at the adja-

cent edges of each ring adapted to be riveted together to form the shell 1 and to assemble the sections near the site of the pier. The shell 1 may be reinforced by internal cross-braces 5 outside the lines of the foundation to be constructed and also by external piles 6, preferably of timber, and by batter piles 7, and a circular working platform 8 may be supported on the piles 6.

The soft material within the shell 1 in the bed of the water is removed by dredging, and the shell is filled with sand or similar granular material to a level at or near the surface of the water. The water remaining in the shell 1 is then pumped out thus providing a substantially dry island upon which the caisson 9 of any desired type may be cast.

The caisson 9 is then constructed on the surface of the sand within the cylinder, the lower extremities of the caisson walls 11 and cross-walls 11^a being preferably shod with metal 12 provided with cutting edges 13. The caisson is then lowered through the sand within the shell and into the bed of the water below the sand, section by section, by alternately dredging the wells 10 and building up the caisson walls, so that each succeeding section of the caisson will be formed above the water in the dry. When the sinking of the caisson has reached a point where it rests on the rock, or other foundation bed, the sand or other granular material is removed from the shell outside of the caisson, and the shell, or that part of it which is above the bed of the water, may be removed and used again in preparing the foundation for other piers.

After the caisson is completed and rests upon bed rock, or other foundation bed adequate to support the load to be carried, the foundation for the pier may be completed in any of the usual ways common to engineering practice.

Having described our invention what we claim is new and desire to protect by Letters Patent is:

1. The method of preparing a foundation for subaqueous piers or the like, which consists in placing a shell around the site of the proposed pier and extending above high water line, then placing granular material

within the shell, then constructing a caisson upon the island thus formed within the shell and sinking the caisson in the granular material.

5 2. The method of preparing a subaqueous foundation or the like, which consists in placing a steel shell at a depth which will provide a stable support, then filling the shell to substantially the top with granular material, 10 then lowering the caisson through the granular material inside the shell and into the solid ground below the same so that the entire caisson may be constructed above water in the dry, then removing the granular material from the outside of the caisson and the shell above the natural ground.

3. The method of preparing a subaqueous foundation or the like, which consists in placing a steel shell around the site of the 20 proposed foundation with the top of said shell above the water line, then filling the shell to substantially the top with granular material, then lowering a caisson through the granular material inside the shell and 25 into the solid ground below the same by alternately dredging and building up the caisson walls so that the entire caisson may be constructed above water in the dry, then removing the granular material from the 30 outside of the caisson and the shell above the natural ground.

4. The method of preparing a subaqueous foundation or the like, which consists in placing a steel shell around the site of the 35 proposed foundation with the top of said shell above the water line and its base resting on the ground, then filling the shell to substantially the top with granular material, then lowering a caisson through the granular 40 material inside the shell and into the solid ground below the same by alternately dredging and building up the caisson walls so that the entire caisson may be constructed above water in the dry.

45 5. The method of preparing a subaqueous foundation or the like, which consists in placing a steel shell around the site of the proposed foundation with the top of said shell above the water line, then filling the shell 50 to substantially the top with granular material, and constructing a caisson provided with cutting edges at the base of its outer and cross walls and lowering the same through the granular material inside the shell and 55 into the solid ground below the same by alternately dredging and building up the caisson walls.

6. The method of preparing a subaqueous foundation or the like, which consists in placing a steel shell around the site of the 60 proposed foundation with the top of said shell above the water line, then filling the shell to substantially the top with granular material, then casting in sections and lower- 65 ing a caisson through the granular material

inside the shell and into the solid ground below the same by alternately dredging and building up the caisson walls so that the entire caisson may be constructed above water in the dry.

7. The method of preparing to construct a subaqueous foundation, which consists in placing a shell around the site of the proposed foundation, then filling the shell with granular material to form an island, and constructing a caisson upon the island thus formed within the shell and sinking the caisson through the granular material to the bed upon which the foundation is to rest.

8. The method of preparing to construct a subaqueous foundation, which consists in placing a shell around the site of the proposed foundation, then filling the shell with granular material to form a temporary island, then constructing a caisson upon said island and removing the greater part of said granular material.

In testimony whereof, we have hereunto signed our names to this specification.
